DESIGN FOR AN EVENING WRAP

Frank Proto, New York, N. Y.

Application August 12, 1940, Serial No. 94,392

Term of patent 3½ years

To all whom it may concern:

Be it known that I, Frank Proto, a citizen of the United States, residing in New York city, in the county of New York and State of New York, have invented a new, original, and ornamental Design for an Evening Wrap, of which the following is a specification, reference being had to the accompanying drawing, forming part thereof.

Fig. 1 is a front view of an evening wrap showing my design, and

Fig. 2 is the rear view thereof on a reduced scale.

I claim:

The ornamental design for an evening wrap, substantially as shown.

FRANK PROTO.
